By Fisher, Towle, Cleppitt, Brown, Atys

UNITED STATES PATENT OFFICE.

HAROLD G. RICE, OF CHICAGO, ILLINOIS.

BOTTLE CAPPER.

Application filed February 5, 1927. Serial No. 166,095.

My invention relates to bottle cappers, but more particularly to that type in which there is provided a frame with a base, an upright member or rack on the frame, a rider slidably

5 on the upright member and carrying a pivoted lever having means co-operating with the upright member, such as a segment, engaging the rack to operatively connect the two, whereby the rider may be reciprocated to move a cap-
10 ping head thereon into and out of capping position.

The invention further relates to a bottle capper having a lever which is depressed by hand to apply a cap to a bottle and which, up-
15 on the lever being released after the capping operation, will cause the lever to be raised to an inoperative position and the capping head out of capping position, whereby the lever will not only be in convenient position for op-
20 eration in applying another cap and in removing the bottle and inserting a new one beneath the capping head, but will obviate the necessity of holding the lever in a raised position by one hand in order to permit the in-
25 sertion of the bottle beneath the capping head, thus leaving both hands free to carry on the capping operation.

The present device is also an improvement on the devices shown in my Reissue Patent
30 No. 15,222, dated November 8, 1921, and my co-pending application Serial No. 27,378, filed May 2, 1925, the improvements consisting in the construction of the frame and rider and in strengthening the frame and other
35 parts to withstand the strains to which the device is subjected in use, whereby to lengthen the useful life thereof.

The particular embodiment in connection with the present invention resides in the construction of the frame and the rider, including the mounting of the rack bar, and the object thereof is to provide a novel and rigid frame having a base in which the bottles are supported during the capping operation and
45 which will accommodate bottles of different designs and sizes and will permit them to be properly supported in position beneath the capping head, as well as to prevent displacement of the bottles accidentally, and to so
50 construct the upright member or rack bar and rider that the latter will have free sliding

movement during the operation of the device without binding, and to generally improve the appearance and enhance the value of devices of this nature.

55

In the accompanying drawings:—

Fig. 1 is a side elevation of the bottle capper constructed in accordance with the invention.

Fig. 2 is a sectional elevation taken on the line 2—2 of Figure 1.

60

Fig. 3 is a fragmentary vertical sectional view of the device with parts thereof shown in elevation.

65

Fig. 4 is a horizontal sectional view taken on the line 4—4 of Figure 1, and

Fig. 5 is a horizontal view taken on the line 5—5 of Figure 2.

65

Referring to the drawings in detail, the capper comprises a frame or standard 6 including a base or foot plate 7 preferably of substantially oval or elliptical outline or form in plan and having apertured attachment lugs or ears 8 desirably located at the front and one at each side near the back for receiving fastening means to secure the base and frame to a workbench, table, or other supporting surface. The base 7 is preferably pressed-sheet metal with parts thereof disposed in three horizontal planes. The peripheral portion 9 is pressed down to form an attaching flange inwardly of which is disposed an upstanding annular stiffening rib or raised shelf 10 and inwardly thereof is disposed a central depressed portion or pan 11 in and on which the bottle to be capped is adapted to be supported. The portion 11 is disposed in a plane between the parts 9 and 10 and may be spaced from the supporting surface of the bench or table, as clearly shown in Figure 2 of the drawings.

80

The head or rib 10 receives and supports the frame 6 thereon and has slotted inwardly extending projections 12 at the sides near the rear and at the back to receive in the slots thereof attachment means of the frame 6 proper. This frame is preferably of sheet metal suitably formed or shaped, but may be die cast or otherwise produced. It is of substantially concavo-convex or U-shaped cross-section and has its lower edge formed with attachment lugs 13 located at the forward edges 95 and at the back thereof and which extend through the slots in the projections 12 and

95

100

are turned over or bent at right angles beneath the walls thereof to rigidly and fixedly connect the parts of the frame—that is, the upright part or frame proper to the base. The frame 6 preferably enlarges downwardly and the forward edges 14 thereof are concave and inclined slightly forwardly toward their lower ends to give more substantial support and better retain the bottle in position and against lateral displacement. The rear portion extends substantially vertically while the sides are convexed or bowed outwardly in symmetrically curved formation, so that the frame tapers or merges at the top of its bottle-receiving portion at the lower half of the frame to the point 15 where it is reinforced internally into an upright or vertical upper bar portion 16 having a tubular portion 17 and sides 18 branching forwardly therefrom in slightly restricted spaced parallel relation and directed forwardly at right angles at their lower ends as indicated at 19. A rack bar 20 is held between these portions 18 and preferably comprises two plate sections or strips 21 having notches co-operating to form the rack bar 20, the strips being anchored between the portions 18 as by means of rivets or other fasteners, as at 22, positioned at suitably spaced points along the lengths of the parts. The lower ends of the strips 21 rest on the shoulder formed by the merging of the sides of the frame 6 at the juncture 15, these portions serving to strengthen the frame at the point where it is reduced in size and bent to form the upper guide frame which carries the rack bar.

A rider 23 is slidably mounted on the upper portions 16 of the frame and is fashioned from a single plate formed into a tubular portion 24 which fits and slides on the tubular part 17 of the upper guide part or rack bar of the frame. Like the sides 18, the sides 25 of the plate or strip from which the rider is formed, are extended in spaced parallel relation restricted in spacing with respect to the diameter of the tubular portion 24 so as to fit against the portions 18 and have uniform guiding movement when slid or reciprocated thereon. The sides 25 have inwardly offset apertured ears 26 at their upper ends formed as extension lugs on the sides of the plate of which the rider is formed and connected by a rivet or other fastening means 27, such securing means between the ears keeping the rider in shape. Beneath the ears 26 the rider is provided with opposite forward extensions 28 suitably spaced apart as by a notch 29 in the lower edge of one extension defining an inner wing 30 prolonged transversely of the rider into engagement with the other extension so as to secure such parts uniformly in spaced relation and at the same time provide an apertured ear or lug 31 projecting through a notch 32 of the second extension or secured to the outer face thereof. One of the exten-

sions 28 is also provided with an extension 33 which is prolonged transversely between the extensions 28 at the bottom of the slot therebetween to engage a corresponding recess 34 in the other side or extension 28 to limit the downward movement or swing of a handle 35. This handle is mounted on a pivot 36 engaged in opposite horizontally aligned apertures in the extensions 28 but preferably in the form of a rivet having the ends thereof headed or upset so as to restrain the extensions 28 from outward displacement. The lever preferably has its outer or gripping portion shaped from a bent piece of metal to fit the contour of the hand in grasping the same and an inner portion 37 comprising a pair of plates riveted between the sides of the portion 35 as indicated at 38 and their inner edges formed with co-acting teeth providing a toothed segment or segmental rack 39 meshing with the rack bar 20. The extension 33 limits the downward swing of the handle when depressed by engagement with the shank thereof when moving the capping head 40 into capping position. This capping head is carried by the extensions 28 at their lower edges and is preferably riveted to reduced portions 41 extending downwardly from the extensions 28 and through slots in the end wall of the head as indicated at 41. This capping head has an apertured cushion 42 therein and is designed to receive the bottle caps in the application thereof to the bottles.

Also mounted on the shaft 36 outwardly of an extension 28 is a dog 43 which may be in the form of an angular cross-arm 43 for which the pivot 36 forms a fulcrum and is retained in position by the adjacent headed end thereof. The forwardly extending arm has an outwardly extending or angular portion 44 in the form of an apertured lug or ear for connection of a contractile spring 45 therewith at one end, the opposite or lower end of the spring being anchored to the rider 23 at the ear 31 adjacent to its bottom edge. Obviously, the ear 31 may be formed in any suitable manner as by stamping or pressing the same out from the bottom edge of one side or extension of the rider. The same arm of the dog or cross-arm has a lateral inward extension 46, which is designed to engage in back of the rider above the extensions 28 to limit the pivotal movement of the cross-arm or dog under the tension of the spring 45. The other free end of the dog or cross-arm which extends rearwardly has a lateral inward extension 47 which extends under the lever and is designed to engage the shank of the handle or lever 35, whereby the lever is held in a raised position under the action of the spring 45 limited by the extension 46 as shown in Figure 1 of the drawings, so that the lever in the uncapping or inoperative position is normally in a substantially horizontal posi-

tion or slightly elevated above horizontal. In this raised position the lever can be conveniently actuated and when so supported both hands of the operator are free to place 5 and remove the bottles, as well as to apply the caps, or for other purposes. At the same time the capping head 40 will clear the top of the bottle and it will not be necessary to first raise the capping head by raising the lever 10 before the bottle can be inserted and the cap applied.

In the operation of the device, when a cap is being applied, the bottle is mounted on the base 7 in the part 11, so that the neck of the 15 bottle will be beneath the capping head. A cap having been previously placed in the capping head, the operator then presses down on the lever 35 and applies the cap to the bottle, owing to the downward movement 20 of the rider, by rocking of the segment 39 on the rack 20. During the downward movement of the lever, the shank thereof engages the extension 47 and rocks the cross-arm or dog 43 on its pivot 36, which is common to 25 the fulcrum of the lever, and raises the forward arm to stretch or extend the spring 45 against its tension, at the same time moving the extension or stop 46 away from the rider. Upon releasing the pressure from the lever 35 30 the spring 45 will react and cause the extension 47 to engage the lever and raise it to a slightly elevated and operative position. This movement will also swing the rack segment at the inner end of the lever down and 35 raise the rider until the extension 46 contacts with the rider. In this position the capping head will have been elevated automatically and removed or raised away from and above the bottle neck and cap thereon, thus 40 obviating the possibility of the lever dropping down and obstructing the work by interfering with the free insertion of the bottles or caps or requiring manual elevation thereof. Normally the lever will be supported in a sub- 45 stantially horizontal position but preferably slightly inclined above horizontal in convenient position for use, but may be swung upwardly to a substantially vertical position to disengage the teeth of the segment 39 from 50 the teeth of the rack bar 20 to permit free sliding movement of the rider 23 over the teeth of the rack bar or the frame or upper portion thereof whereby quick initial adjustment of the rider and capping head to bottles of 55 different sizes or heights may be obtained. The upward swing of the lever 35 will be independent of the dog or cross-arm 43—that is, the lever will move away from the supporting lug or extension 47 while the cross-arm is 60 held against movement under the tension of the spring 45 limited by the engagement of the stop lug or extension 46 with the rider. The tubular formation of the upper part of the frame or rack bar at 17 and the corresponding 65 fitting engagement of the tubular portion 24

of the rider not only strengthens or stiffens the upper portion of the frame but insures a connection between the parts which will avoid unnecessary play or canting of the rider, tending to move to a diagonal position and causing its corners or ends to grip or bind, but will insure free and uniform reciprocation of the rider when actuated and generally facilitate the capping of the bottles. The frame at the point 15 is strengthened by a tubular wall formation at the inside which produces a seam, as clearly shown in Figures 2 and 3 of the drawings, although this seam may be closed if desired.

While I have shown and described my invention in a preferred form, I am aware that various changes and modifications may be made therein without departing from the principles of the invention, the scope of which may be determined by reference to the appended claims.

I claim as my invention:

1. In a bottle capper, a frame of concavo-convex cross-section having an upright portion with a tubular part and parallel side 90 portions extending therefrom, a notched bar secured between said side portions, and a base secured to the lower portion of the frame.

2. In a bottle capper, a frame of concavo-convex cross-section having an upright portion with a tubular part and parallel side 95 portions extending therefrom, a notched bar secured between said side portions, means for holding the frame in an upright position, a rider slideable on the upright portion of the frame over the notched bar and having a tubular portion fitting the first-mentioned tubular portion, a lever pivoted on the rider and having a notched segment engaging the notched bar, and a capping head on the rider. 100

3. In a bottle capper, a frame of concavo-convex cross-section having an upright portion with a tubular part and parallel side 105 portions extending therefrom, a notched bar secured between said side portions, means for holding the frame in an upright position, a rider slideable on the upright portion of the frame over the notched bar and having a tubular portion fitting the first-mentioned tubular portion and extended sides embracing the side portions of the upright portion, a lever pivoted on the rider and having a notched segment engaging the notched bar, and a capping head extending down to the rider in front of the frame at its concave side, movement of the lever causing the rider to slide. 110

4. In a bottle capper, a frame in the form of an upright sheet metal member of substantially U-shaped cross section with its open side disposed forwardly and enlarging downwardly, a base forming a bottle support and connected to the lower end of the frame, and the sides being brought toward each other 115 to form an upright portion extending up- 120

wardly from the narrow upper end of the frame with spaced side portions extending therefrom, and a bar held between said side portions.

5. In a bottle capper, a frame in the form of an upright member of substantially U-shaped cross section with its open side disposed forwardly and enlarging downwardly, a base forming a bottle support and connected 10 to the lower end of the frame, said frame being formed at its upper end with an upright part having a tubular portion and spaced parallel sides restricted with respect to the diameter of the tubular portion, and a rack 15 bar held between said sides.

6. In a bottle capper, a frame in the form of an upright member of substantially U-shaped cross section with its open side disposed forwardly and enlarging downwardly, 20 a base forming a bottle support and connected to the lower end of the frame, said frame being formed at its upper end with an upright part having a tubular portion and spaced parallel sides restricted with respect 25 to the diameter of the tubular portion, a bar secured between said sides, a rider having a tubular portion and spaced sides extending therefrom fitting the tubular portion and spaced sides aforesaid, and means on the rider 30 having operative engagement with the bar for reciprocating the rider, said rider having a capping head.

7. In a bottle capper, a frame in the form of an upright member of substantially U-shaped cross section with its open side disposed forwardly and enlarging downwardly, 35 a base forming a bottle support and connected to the lower end of the frame, said frame being formed at its upper end with an upright part having a bearing portion and spaced sides projecting forwardly therefrom, a bar secured between said sides, a rider having a tubular portion fitting said bearing portion and spaced sides extending therefrom fitting 40 the spaced sides aforesaid and embracing the edges thereof, said rider having a depending capping head at the front of the capping frame, and means on the rider and having 45 operative engagement with the bar for sliding the rider into and out of capping position.

8. In a bottle capper, a single sheet metal transverse frame member of substantially U-shaped cross section with an intermediate bight portion closing the frame member at 55 the back and enlarging downwardly with diverging sides and having extensions on its lower edge, a base having openings receiving the extensions for attaching the frame member to the base, the upper end of the frame member being formed with an upright and the sides of the frame member brought toward each other in tapering formation at the juncture with the upright and a rider movable on the upright and having a capping head.

9. In a bottle capper, a sheet metal frame

of substantially U-shaped cross section enlarging downwardly with diverging sides and having extensions on its lower edge, a base having openings receiving the extensions for attaching the frame to the base, said frame having its wall offset inwardly and continued upwardly to form an integral upright portion reinforced at its juncture with the frame proper and spaced sides, and a notched bar held between said sides.

10. In a bottle capper, a sheet metal frame of substantially U-shaped cross section enlarging downwardly with diverging sides and having extensions on its lower edge, a base having openings receiving the extensions for attaching the frame to the base, said frame having an integral upright portion with a substantially tubular part and spaced sides extending therefrom with forward extensions at their lower ends, a rack bar held between said sides, a rider conforming in shape to the upright portion and movable over the same, a lever pivoted on the rider and having a toothed segment engaging the rack to reciprocate the rider, and a capping head on the rider.

11. In a bottle capper, a sheet metal frame of concavo-convex cross section having an open side and tapering toward its upper end, 95 said upper end being extended to form a guide frame and having stiffening portions, the lower edge of the frame having tongues, and a base having a marginal raised portion with slots receiving the tongues which are turned over to secure the base to the frames.

12. In a bottle capper, a sheet metal frame of concavo-convex cross section having an open side and tapering toward its upper end, 100 said upper end being extended to form a guide frame and having stiffening portions, and a base for the frame having a peripheral flange, an upstanding rib or shelf on which the frame rests and to which the lower edge of the frame is secured, and a pan inwardly 105 of the rib to receive the bottles, the frame being disposed at the back of the base so that the forward part of the base projects therefrom.

13. In a bottle capper, a frame in the form of an upright member of substantially U-shaped cross section with its open side disposed forwardly and enlarging downwardly, 110 a base forming a bottle support and connected to the lower end of the frame, said frame being formed at its upper end with an upright part having a tubular portion and a rack bar, a rider having a tubular portion fitting the tubular portion aforesaid, a capping head on the rider, and means pivoted on the rider and having operative engagement with the bar for reciprocating the rider into and out of capping position.

14. In a bottle capper, a frame of concavo-convex cross-section having an upright portion with a tubular part and side portions 115

extending therefrom, a bar secured to said side portions, means for holding the frame in an upright position, a rider slideable on the upright portion of the frame over the 5 bar and fitting the tubular part, a lever pivoted on the rider and having operative connection with the bar for reciprocating the rider upon movement of the lever, and a capping head depending from the rider in 10 front of the frame.

15. In a bottle capper, a frame in the form of an upright member of substantially U-shaped cross section with its open side disposed forwardly and enlarging downwardly, a base forming a bottle support and connected to the lower end of the frame, said

frame being formed at its upper end with an upright part having a tubular portion and spaced parallel sides restricted with respect to the diameter of the tubular portion, a bar secured between said sides and projecting forwardly thereof, a rider having a tubular portion and spaced sides extending therefrom slidably fitting the tubular portion and spaced sides together with 20 the forward edges thereof and the sides of the bar, a capping head on the rider, and means pivoted on the rider and having operative engagement with the bar for reciprocating the rider into and out of capping position. 25

HAROLD G. RICE.
